UNITED STATES PATENT OFFICE.

TRUSTIN B. BOYD, OF ST. LOUIS, MISSOURI.

COPYING-PRESS.

SPECIFICATION forming part of Letters Patent No. 388,817, dated September 4, 1888.

Application filed June 14, 1886. Serial No. 205,162. (No model.)

To all whom it may concern:

Be it known that I, TRUSTIN B. BOYD, of St. Louis, Missouri, have made a new and useful Improvement in Copying-Presses, of which the following is a full, clear, and exact description.

This improvement is supplementary to that patented to me February 16, 1886.

It relates to the construction of the several parts and their combination together in a copying-press, all as will now be more fully set forth and explained.

In the annexed drawings, making part of this specification, Figure 1 is a horizontal section on the line 1 1 of Fig. 2. Fig. 2 is a vertical longitudinal section on the line 2 2 of Fig. 1. Fig. 3 is a view in perspective of the improved machine, and Fig. 4 is a longitudinal section of the receiving-reel.

The same letters of reference denote the same parts.

20 B represents the machine frame.

A represents the delivery-reel, upon which the web of paper for taking the impressions is wound.

25 The web C, as shown in Fig. 2, leads from the reel A under the water tank G, upward past the farther side of the tank, thence over the tank, the longitudinal edges at top and bottom of which are rounded for the purpose,

30 and between a roll, D², which is adapted to be rotated in the water g of the tank, and the roll D, immediately above the roll D². The web is then carried half around the roll D and between it and the roll D' above the roll D, and thence it is carried to and wound upon the receiving-reel F. The rolls D² D D' are respectively attached to the shafts d' d d', the reel A to the shaft a, and the reel F consists of a sleeve, f, upon a shaft, f', which is provided

35 with a pulley, f'. A belt, E, leads from a pulley, d', upon the shaft d to the pulley f'. Motion is communicated to the working parts of the machine by means of the crank H, which is attached to the shaft d, and when the crank is rotated the web C is drawn through the rolls in the manner shown and described and wound upon the reel F.

In the original construction above referred to the paper passed directly through a pair of 45 rolls corresponding to the two rolls D² D of the present construction, and in so doing came in contact with the rolls at a single point only.

By reason of this the paper was not thoroughly dampened. The difficulty is overcome by employing the three rolls D² D D', as shown, for 55 by the time the paper has passed the middle roll in the manner described it is sufficiently moistened for the purpose in view. As the web is wound upon the reel F, the reel increases in diameter, and were it not for the provision about to be described the tension upon the web would become so great as to cause the web to part between the rolls D D' and the receiving-reel. To prevent this, the sleeve f is 60 not fastened to the shaft so as to be controlled by the shaft, but is sufficiently loose thereon to be in its rotation controlled rather by the web—that is, the sleeve fits the shaft closely enough to be carried by friction around with it, saving when the web draws backward upon it, whereupon it slips upon the shaft accordingly. The belt E can also be made to slip upon the pulleys to prevent the web from parting. Upon the delivery end of the machine-frame is a blade or edge, preferably in the 65 form of the serrated strip I, Figs. 1, 2, and 3, for severing the web, after it has been wound upon the receiving-reel, into sheets, the desirable practice in this respect being to wind the web onto the reel and allow it to remain 70 there until it has dried, after which it can be unwound from the reel F and drawn over the part I and thereby severed into any desired length. The reel F need not in all cases be used, and the web, as the copying is done, may 75 be drawn over the blade I and severed, as described.

The shaft of the reel F may have a part, f³, Fig. 4, fastened to it, in which case the sleeve f is loose on the part f³, or the parts f' f³ may 80 be one piece.

I claim—

In a copying-press, the combination of the tank G, having rounded bottom and top edges, with the paper-reel A, the rolls D D², and the 85 reel F, whereby the paper is fed beneath the tank and over its edge and around the roll D to the reel F, the several parts constructed and operating substantially as described.

Witness my hand.

TRUSTIN B. BOYD.
